UNITED STATES PATENT OFFICE.

MCLEOD THOMSON, OF CHELSEA, NEW JERSEY, ASSIGNOR TO THE RAIL JOINT COMPANY, OF NEW YORK, N. Y., A CORPORATION OF NEW YORK.

CONSTRUCTION FOR HEAD-FREE RAIL JOINTS.

Application filed February 7, 1927. Serial No. 166,440.

This invention relates to a supplementary feature of improvement for the head-free type of rail joint wherein the joint bar has a bearing in and at the head fillet of the rail.

5 A distinguishing characteristic of the head-free rail joint of the type disclosed in the reissue patent of W. P. Thomson No. 15,773 granted February 19, 1924, is to provide the head of the joint bar with a clearance from the underside of the rail head, and with a loading engagement at the head fillet of the rail. Such an anchorage for the inner head projection of the rail joint bar has been found most effectively to assimilate 10 the loading and deflection forces to which a rail joint is subjected, and to bring the head of the bar into solid resistance to load deflection.

In the application and adjustment of the 20 head-free joint, the base of the bar moves inwardly thereby oscillating the bar on a longitudinal axis located approximately within the region of the bolt holes causing the head of the bar to ride upwardly and 25 outwardly on the rail which inclines the outer bolting face of the bar toward and against the upper portions of the nuts (and bolt heads). This action slightly cant's the bolting face downwardly and inwardly from 30 its normal vertical plane, and serves to act as a nut lock.

This adjustment occurs, however, without materially spreading the out-to-out distance between the opposite splice bars along the 35 plane of the center line of the bolt holes, thereby obviating excessive increase of the bolt strain. At the same time there necessarily is some deflection, due to this adjustment of the joint or splice bar, of the bolt 40 ends, and it is the purpose and intent of the present invention to provide an improvement which reduces the amplitude of movement of the bolt ends.

A principal object, therefore, of this 45 invention is to provide a bolt-conserving construction for head-free rail joints which minimizes the deflection of the bolt ends, thereby obviating excessive or abnormal strains being set up therein due either to 50 tightening up the joint when applying the joint bars, or to the subsequent tightening

of the bolts to take up adjustment for any wear that might occur on the lower fishing surfaces over the rail base flanges.

While the invention is susceptible of structural modification without departing from the spirit or scope thereof a preferred and practical embodiment is shown in the accompanying drawings in which

Fig. 1 is a cross sectional view of a head-free rail joint, embodying the present improvement and showing the initial relative position of the various parts prior to the inward oscillation of the bars under the force of the tightening of the nuts.

Fig. 2 is a view of one joint bar showing by full and dotted lines the feature which provides for each nut (and bolt head) initially tightened against the bolting face with the inner nut face in a downwardly and outwardly slanting plane, and subsequently assuming a vertical plane and then a downwardly and inwardly slanting plane.

Fig. 3 is a view of a modification showing how the bolting face can be formed to present a downwardly and outwardly inclined nut bearing by forming a bearing rib or projection below the center line of the bolt holes.

Fig. 4 is an elevation of the modified bar of Fig. 3 shown applied to the rails.

In practicing the present invention all of the desirable and characteristic features of the head-free rail joint are preserved and maintained, so for illustrative purposes there is shown in the drawings a rail joint of that type which includes the rail R having the rounded head fillet bearings 1-1, each head fillet bearing providing the anchorage for the inner head projection 2 of the joint bar 3 whose foot portion 4 has a fishing engagement with the lower fishing bearing 5 provided at the upper side of the rail base flange.

According to the present invention, as above pointed out, it is proposed to make an alteration of, or on, the bolting face of the joint bar against which is clamped the head 6 and nut 7 of the joint bolt 8, and as the action of the bolt at the head end thereof is the same as at the nut end it will be understood that reference herein to the nut and to

the nut bearing will apply equally to the head of the bolt, and the terms are therefore intended to include the bolt head.

In the embodiment of the invention shown in Figs. 1 and 2 of the drawings the object of the invention is attained by providing the joint bar at its outer side with a canted bolting face 9 which presents a nut bearing that inclines downwardly and outwardly from the vertical plane of the bar indicated by the line *a*—*a* on Fig. 1. In other words the said bolting face or nut bearing may be said to be downwardly divergent with reference to the central perpendicular axis of the bar, *x*—*x*.

The effect of the construction described is to dispose the bolting face of the bar that its characteristic oscillation, as the wear on the lower fishing face of the bar progresses, causes the bolting face or nut bearing first to assume a vertical position and afterward to change to a downwardly and inwardly slanting position. This oscillation of course is produced by the initial tightening of the nuts and the subsequent tightening of the nuts to take up the wear referred to.

It will be seen from the illustration of Fig. 2 of the drawings that in the initial tightened condition the nut on the bolt takes a bearing against and in parallelism to the canted bolting face thereby tending to deflect, and actually deflecting the end of the bolt upwardly as indicated by the full line *b*. Then as the progressive oscillation of the joint bar occurs, under further tightening, the bolt end will deflect back to the horizontal indicated by the dotted line *c* and then deflect below the horizontal plane to its downwardly deflected position indicated by the full line *d*. However, it will now have been observed that the upward and downward deflection of the bolt end will be equally divided, as to amplitude, above and below the horizontal, with the result of greatly reducing the bolt strain that is likely to occur where the bolt end deflects all in one direction in the case of a joint bar having an initially vertical bolting face, and the entire oscillation of the joint bar, under adjustment being inwardly from a vertical plane.

On Fig. 2 of the drawings the dotted lines *a* and *e* respectively designate the progressive planes assumed by the bolting face of the joint bar as the lower part of the bar swings or oscillates inwardly first to the vertical plane, and finally to an inwardly and downwardly slanting plane.

In Figs. 3 and 4 of the drawings is shown the modification wherein the inclined bolting face, or nut bearing, designated by the reference number 9^a may be provided by forming the bar on its outer side with a bearing rib or projection 10 arranged below the center lines of the bolt holes and prefer-

ably at the bottom of the bolt holes so that the nut or nut washer and the bolt head can take the downwardly and outwardly canted or inclined position upon the initial tightening.

Other modifications of the invention will be now apparent to those familiar with the art and it also will be understood that changes in the form, proportion and minor details of construction may be resorted to without departing from the spirit or sacrificing any of the advantages of the invention.

I claim:

1. A construction for head-free rail joints including in combination with the rails and the clamping bolts, a head-free splice bar provided with an outer bolting face presenting a nut bearing which inclines downwardly from the vertical plane of the bar.

2. A construction for head-free rail joints including in combination with the rails and the clamping bolts, a head-free splice bar provided with an outer bolting face presenting a nut bearing which slants downwardly and outwardly from the vertical plane of the bar.

3. A construction for rail joints including the rails, clamping bolts, and a head-free splice bar having its bolting face so disposed in relation to the central vertical plane of the bar that the characteristic oscillation of the plane of the bolting face first causes this plane to assume a vertical position and subsequently to shift to a downwardly and inwardly slanting position.

4. A construction for rail joints including the rails, clamping bolts, and a head-free splice bar having a bolting face presenting a nut bearing so disposed in relation to the central vertical plane of the bar that the plane of the inner face of each nut when tightened is caused first to assume a downwardly and outwardly slanting position and subsequently to progressively assume a vertical position and a downwardly and inwardly slanting position.

5. A construction for head-free rail joints including the rails, clamping bolts, and a head-free joint bar, each nut in its initial tightened position having its inner face disposed in a downwardly and outwardly slanting plane and when subsequently tightened assuming first a position in a vertical plane and finally assuming a position in a downwardly and inwardly slanting plane.

6. A construction for head-free rail joints including the rails, clamping bolts and a joint bar having the major portion of its upper loading engagement with the head fillet of the rail, the initial, medial and final dispositions of the bolting face of said splice bar, as said bolting face is oscillated toward the rails by tightening of the nuts to take up wear, being such that the head end and

the major portion of the threaded end of each bolt will be strained slightly to a position where the center line of each bolt will be tilted, first slightly upward at its ends, ⁵ then will resume alinement with the normal straight center line of the bolt, and finally the aforesaid end portions of each bolt will

be strained slightly to positions where the center line of the bolt will be tilted slightly downward at each end. ¹⁰

In testimony whereof I hereunto affix my signature.

MCLEOD THOMSON.
